Attorney

UNITED STATES PATENT OFFICE.

WILLIAM J. RATEKIN, OF OAKES, NORTH DAKOTA.

GRATE.

1,329,629.

Specification of Letters Patent.

Patented Feb. 3, 1920.

Application filed July 23, 1919. Serial No. 312,828.

To all whom it may concern:

Be it known that I, WILLIAM J. RATEKIN, a citizen of the United States, residing at Oakes, in the county of Dickey and State of

5 North Dakota, have invented certain new and useful Improvements in Grates, of which the following is a specification, reference being had to the accompanying drawings.

10 This invention relates to certain improvements in grates, and it is an object of the invention to provide a novel and improved device of this general character provided with means whereby air is distributed 15 within the fire-bed in a manner whereby an effective combustion is created.

It is also an object of the invention to provide a novel and improved grate of this 20 general character provided with air feeding means whereby the grate is particularly adapted for use in connection with lignite or kindred fuel.

The invention consists in the details of construction and in the combination and arrangement of the several parts of my improved grate whereby certain important advantages are attained and the device rendered simpler, less expensive and otherwise more convenient and advantageous for use, 30 as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in top plan with portions broken away of a grate constructed in accordance with an embodiment of my invention.

Fig. 2 is a sectional view taken substantially on the line 2—2 of Fig. 1.

Fig. 3 is a sectional view taken substantially on the line 3—3 of Fig. 1 with the co-45 acting fire-pot also shown in fragment.

As herein embodied, my improved grate comprises a plate P adapted to be suitably supported within the fire-pot F of a stove or furnace and which plate is herein disclosed 50 with a pair of diametrically opposed openings 1 arranged adjacent the periphery of the plate P. The openings 1 provide for an updraft and also to facilitate cleaning out of the fire-pot.

55 P' denotes a second plate overlying the plate P and rotatably supported by the plate

P at substantially the axial center thereof. The plate P' is elongated with its extremities of a configuration to substantially close the openings 1 when the plate P' is in its 60 normal or one position. An end of the plate P' is provided with an outstanding arm 2 adapted to be engaged by a suitable implement for imparting the requisite rotation to the plate P' when it is desired to uncover 65 the openings 1 and particularly for the purpose of cleaning out the fire-pot F. In order to completely uncover the openings 1 the plate P' is moved or rocked to substantially 70 90 degrees and for which reason the longitudinal marginal portions of said plate P' are provided with the recesses or cut out portions 4 so that when the plate P' is in its second position said plate will offer no obstruction to the openings 1 in the plate P. 75

The plate P' in each of its end portions is provided with a pair of transversely spaced openings 5 which, when the plate P' is in its normal position, are substantially in communication with the openings 1 so that the up-draft through the openings 1 will also pass through the openings 5. Each of the openings 5 is defined by an upstanding flange 6 adapted to snugly fit within a rabbet formed in an end of the member M substantially in the form of an inverted U. A member M coacts with each pair of longitudinally spaced openings 5 and the central or intermediate portion 7 of said member is provided in its lower and side portions with the 80 restricted ports or openings 8 with the ports 8 in the side being inclined in a direction toward the plate P'. The side portions or legs 9 of the member M are also provided with restricted ports 10 inclined in a direction toward the plate P'. The draft passing 85 upwardly through the openings 1 and through the members M is, through the instrumentality of the ports 8 and 10, distributed within the fire-bed in a manner to 90 assure effective combustion. To further support combustion I find it of advantage to provide the wall of the fire pot F with the downwardly and inwardly inclined air ports 11 in communication with the atmosphere 105 and delivering within the fire-pot.

My improved grate, as herein disclosed, is particularly adapted for use in connection with lignite, although it can be employed with the same facility in connection with 110 bituminous coal, and with the effect that the fuel burns with a blue flame and substan-

tially of the character obtained from anthracite coal. The members M materially facilitate combustion as the air discharged through the openings 8 and 10 is effectively admixed with the gases generated from the fuel.

From the foregoing description, it is thought to be obvious that a grate constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. As a new article of manufacture, a grate comprising a plate having diametrically opposed openings in its marginal portion, a second plate rotatably supported by the first named plate, said second named plate substantially closing the openings in the first named plate when said second named plate is in one position, and an air feeding tubular member substantially in the form of an inverted U, the extremities of said member being secured to the second named plate, said second named plate having openings in communication with the tubular member, the walls of said tubular member being perforated.

2. As a new article of manufacture, a grate comprising a plate having diametrically opposed openings in its marginal portion, a

second plate rotatably supported by the first named plate, said second named plate substantially closing the openings in the first named plate when said second named plate is in one position, and an air feeding tubular member substantially in the form of an inverted U, the extremities of said member being secured to the second named plate, said second named plate having openings in communication with the tubular member, the walls of said tubular member being perforated, said second named plate being provided with means for rotating the same.

3. As a new article of manufacture, a grate comprising a plate having diametrically opposed openings in its marginal portion, a second plate rotatably supported by the first named plate, said second named plate substantially closing the openings in the first named plate when said second named plate is in one position, and an air feeding tubular member substantially in the form of an inverted U, the extremities of said member being secured to the second named plate, said second named plate having openings in communication with the tubular member, the walls of said tubular member being perforated, the openings in the second named plate being positioned above the openings in the first named plate when said second named plate is in a position to substantially close the openings of the first named plate.

In testimony whereof I hereunto affix my signature in the presence of two witnesses.

WILLIAM J. RATEKIN.

Witnesses:

A. P. GREY,
FRANK JARVIS.
